SEWING KIT

James Jernigan Sanders, Nashville, Tenn.

Application April 29, 1936, Serial No. 77,046

3 Claims. (Cl. 223—108)

This invention relates to sewing kits; and more particularly to one of a pocket type in which the various elements are compactly enclosed in a cylindrical case, in a unique and efficient manner.

It is desirable to have such a kit occupy the minimum space, with each part performing some useful function and the material readily available. The construction set out in my invention fills all of these requirements.

In the drawing:

Figure 1 is a perspective of the kit;

Figure 2 is a vertical section taken on line 2—2 of Figure 1;

Figure 3 is a vertical section of the core taken on line 3—3 of Figure 2;

Figure 4 is a horizontal section taken on line 4—4 of Figure 3; and

Figure 5 is a vertical section of the inner cap showing needles impaled therein.

Referring to the drawing, in which similar parts are designated by like numerals:

Numerals 6 designates a sewing kit having a casing 7, of metal or other suitable material, the top portion 8 forming a closure and constituting a thimble. Within the casing 7 is a unitary core 9, preferably of wood, having spool grooves 10 and 11 formed on the exterior thereof and an internal bore 12, said bore being exteriorly rabbed at one end 13 to form a flange 14 surrounding the mouth 15 of the bore 12. A cover 16, thimble shaped, and having a substantially flat top surface 17, fits over the mouth 15 and onto the flange 14. Within the bore 12 is placed safety pins 18, needles 19, and similar articles, the needles, pins, or the like, being imbedded in the bottom 20 of the cover 16. Thread 21 is wound in the spool grooves 10 and 11.

Upon the core 9 being placed in the casing 7, the closure 8 in the form of a thimble, rests upon the cover 16 and closely conforms thereto. The cover 16 has tapered sides 22 that exactly coincide with the shape of the closure thimble 8, the cover 16 thus serving as a reinforcing block for the thimble to prevent denting while the kit is being carried.

As actually used, the thimble closure 8 will be removed, the cover 16 removed from the

mouth 15 inverted as shown in Figure 5 and placed on a surface. This brings the needles in immediate position for use since they have previously been inserted in the bottom of the cup. The bottom likewise serves as a convenient medium to receive the needles when not in use. The core 9 is then removed from the casing 7 and the thread and contents of the kit are readily available.

It is thought that the invention and numerous of its attendant advantages will be understood from the foregoing description, and it is obvious that changes may be made in the form, construction and arrangement of the several parts without departing from the spirit or scope of my invention or sacrificing any of its attendant advantages, the form herein described being a preferred embodiment for the purpose of illustrating my invention.

What I claim is:

1. Sewing kit including a casing, a unitary core within said casing having an internal bore, said core being exteriorly rabbeted at one end defining a flange surrounding the mouth of said bore, a thimble forming a cover for said casing, and a lid for said core externally thimble-shaped and underlying the thimble for supporting the same, said lid having a bore telescoping on said flange and a counter-bore with penetrable bottom in which needles housed in the core are adapted to be impaled.

2. A sewing kit comprising a casing, a core within said casing having an internal bore, said core having a cover, a thimble forming a closure for said casing, said cover being externally shaped to closely contact the sides and top of said thimble closure for supporting the same.

3. A sewing kit comprising a casing, a core within said casing having an internal bore, said core having a cover, a thimble forming a closure for said casing, said cover having its interior formed with a counter-bore having a penetrable bottom in which needles housed in the core are adapted to be impaled, the top of said cover being flattened so as to support said cover in upright position and display the needles impaled therein.

JAMES JERNIGAN SANDERS.
